FIG. 1 is a perspective view from the front, top and right side of an optical receiver/transmitter module showing our new design;

FIG. 2 is a perspective view from the rear, top and left side thereof;

FIG. 3 is a front elevational view thereof;

FIG. 4 is a top plan elevational view thereof;

FIG. 5 is a rear elevational view thereof;

FIG. 6 is a bottom plan view thereof;

FIG. 7 is a left elevational view thereof; and,

FIG. 8 is a perspective view from the rear, bottom and left side thereof.

*FIG. 1**FIG. 2**FIG. 3*

FIG. 4

*FIG. 5**FIG. 6*FIG. 7

FIG. 8
